UNITED STATES PATENT OFFICE.

ROSWELL H. RAUSCH, OF PLAINFIELD, NEW JERSEY, ASSIGNOR TO NILES-BEMENT-POND COMPANY, OF NEW YORK, N. Y., A CORPORATION OF NEW JERSEY.

SADDLE-TRAVERSING MECHANISM.

Application filed December 20, 1923. Serial No. 681,784.

To all whom it may concern:

Be it known that I, ROSWELL H. RAUSCH, a citizen of the United States, residing at Plainfield, in the county of Union and State of New Jersey, have invented certain new and useful Improvements in Saddle-Traversing Mechanism, of which the following is a specification.

This invention relates to machine tools and particularly to improved means for traversing a saddle or carriage along a guideway of the machine either by hand or power. In radial drills, lathes and like machines, it is necessary to very frequently traverse the tool carriage along its supporting ways to different positions on the machine. Ordinarily for short distances and fine adjustments, this traversing can best be accomplished manually but the longer traversing operations can be more efficiently accomplished by power. The primary object of my invention is to provide improved means for manually and power traversing the saddle or carriage of a machine tool with greater ease and efficiency.

It may frequently be necessary to power traverse the saddle to the approximate position desired and then manually adjust the same. My invention contemplates means including a single manually operated member for operatively controlling the power traversing of the saddle and adjusting the same manually. Another object of my invention is therefore the provision of mechanism for operatively traversing the saddle by hand and power and a single manually operated member for operating and controlling such mechanism.

While my invention contemplates the power traversing of the saddle from any source of power, such traversing is preferably accomplished by an independent electric motor. In the drawings, such a motor is illustrated as mounted on the saddle or carriage and is adapted to be controlled by a switch adjacent thereto. A manually operated handle and means cooperating therewith are provided on the saddle for traversing the carriage manually and operating the switch to power traverse the saddle, the handle having two positions respectively for the manual and power traversing. Another object of my invention is to provide a saddle with a traversing motor and im-

proved means including a single operating handle for optionally traversing the saddle either by hand or from the motor.

With the above and other objects in view, my invention consists in the features of construction and operation set forth in the following specification and illustrated in the accompanying drawings. In such drawings annexed hereto and forming a part of this specification, I have illustrated certain embodiments of my invention in connection with certain machine tools but it will be understood that the invention can be otherwise embodied and that the drawings are not to be construed as defining or limiting the scope of the invention, the claims appended to this specification being relied upon for that purpose.

Referring to the figures of the drawings: Figure 1 is a front elevation of a radial drill embodying my invention.

Fig. 2 is an enlarged fragmentary sectional view thereof taken approximately on line 2—2 of Fig. 1.

Fig. 3 is a view taken on line 3—3 of Fig. 2.

Fig. 4 is a diagrammatic view of the motor controlling switch.

Fig. 5 is a view similar to Fig. 2 but showing a modification of my invention.

Fig. 6 is a fragmentary sectional view taken on line 6—6 of Fig. 5.

Fig. 7 is a fragmentary sectional view showing the clutch operating mechanism.

Fig. 8 is a fragmentary sectional view through a lathe carriage and showing my invention in connection therewith, this view being taken on line 8—8 of Fig. 9.

Fig. 9 is a fragmentary front elevation of the mechanism shown in Fig. 8.

Fig. 10 is an end elevation thereof.

In Figs. 1 to 4 of the drawings, I have illustrated my invention in connection with a radial drilling machine. In these figures, 1 indicates the bed of the machine from which rises a vertical column 2. A horizontal arm 3 is adjustably mounted for vertical movement on the column. A drill head supporting saddle or carriage 4 is slidably mounted on the ways 5 of the arm at one side of the column, a gib 6 being provided for holding the saddle on the ways. The drill spindle 7 is adapted to be rotated and fed from a motor 8 operating

through gearing in a box 9 and through an arm shaft 10, as shown in Patents Nos. 1,296,863 and 1,368,294.

In the drawings, I have illustrated rack 5 and pinion means for traversing the saddle along the arm. A rack 11 secured rigidly to the arm is engaged by a pinion 12 on a vertical shaft 13 in the saddle. A bevel gear 14 on the lower end of this shaft 10 is in mesh with a bevel gear 15 on a horizontal tubular shaft 16. The shaft 16 and the operating means therefor are preferably supported by a member 17 secured to the under side of the saddle. The shaft 16 15 can be rotated manually or rotated by a motor 18 as hereinafter described.

The motor 18 is secured to the under side of the member 17 and a pinion 19 on the motor shaft is in mesh with a gear 20 keyed to the shaft 16. The motor is controlled by a switch within a box 21 secured to the rear of the member 17. The switch contact bar 22 is mounted on a rod 23 extending through the member 17 and tubular shaft 16. Springs 24 acting on an arm 25 normally hold the switch arm in the natural position illustrated in Fig. 4. Rotation of the rod and bar to a position A—B will operate to rotate the motor in one direction and rotation of the rod and bar to a position X—Y will operate to rotate the motor in the opposite direction, as will be understood.

A gear 26 is keyed to the forward end 35 of the rod 23 and a member 27 is loosely mounted on the rod between the gear 26 and the hub 28 of the gear 20, anti-friction ball bearings 29 being provided in ways 30 between these three members. A handle 40 31 is pivoted to the member 27 at 32 and can be moved in opposite directions on such pivot to engage teeth 33 and 34 thereof respectively with the teeth of the gears 26 and teeth 35 cut in the hub 28. Springs 45 36 and gravity normally hold the handle in the neutral and disengaged position.

The operation of the mechanism as thus far described is as follows: When it is desired to hand traverse or adjust the saddle along the arm, the operator grasps the handle 31 and moves the same to engage the teeth 34 thereof with the teeth 35. Thus a direct connection is established between the handle and the operating mechanism for the pinion 12 and the operator can rotate the handle 31 and gear 20 in one direction or the other to manually traverse or adjust the saddle as desired. To power traverse the saddle from the motor 18, the operator moves the handle to engage the teeth 33 thereof with the teeth of the gear 26. Thus a direct connection is established between the handle and the switch arm 22 and the operator can rotate the handle and rod 23 in one direction or the other

to place the arm in positions A—B and X—Y and therefore rotate the motor and traversing mechanism in either direction as desired.

As above described, the handle 31 provides a single manually operable member for optionally traversing the saddle manually or making connections to power traverse the same from the motor 18. When released from either of its operating positions, the springs 24 and gravity operate to automatically return the handle to its intermediate and inoperative position. Furthermore the arrangement of the handle and its cooperating members form in effect an interlock which positively prevents the simultaneous engagement of the handle in its two operating positions. It should also be noted that the handle, when engaged with the gear 26 for power traversing, is in no way effected by the movement of the traversing mechanism, the handle being moved only sufficiently to effect the connections illustrated in Fig. 4.

In Figs. 5, 6 and 7, I have illustrated a modified form of my invention wherein the saddle can be power traversed from the arm shaft 10 instead of from the motor 18, as just described. A rack 37 is secured to the arm 3^a and is engaged by a pinion 38 on a vertical shaft 39 carried by the saddle 4^a. A bevel gear 40 on the lower end of shaft 39 meshes with two bevel gears 41 loose on the arm shaft 10 between two saddle bearings 42. A clutch 43 is splined to the arm shaft between the gears 41 and may be shifted into driving engagement with either of such gears.

A shaft 44 carried by the saddle has a bevel gear 45 on its inner end in mesh with the two bevel gears 41. A clutch operating rod 46 extending through this shaft has a disk 47 on its inner end in which is eccentrically mounted a pin 48 engaging in the groove 49 of the clutch. Rotation of the rod in one direction or the other is adapted to shift the clutch respectively into engagement with the two bevel gears 41 and thereby rotate the traversing pinion 38 in one direction or the other as desired. A spring 50 mounted on the saddle and engaging in the groove 49 of the clutch normally holds the clutch in the neutral position illustrated in Fig. 6.

The mechanism for operating the shaft 44 and the rod 46 from the handle 31^a, and now to be described is substantially the same as that shown and heretofore described in reference to Figs. 1 to 4 of the drawings. A gear 26^a is keyed to the forward end of the rod 46 and a member 27^a is loosely mounted on the rod between the gear 26^a and a gear 51 on the shaft 44, anti-friction ball bearings being provided between these three members. The handle 31^a

is pivoted to the member 27^a at 32^a and can be moved in opposite directions on such pivot to engage the teeth 33^a and 34^a thereof respectively with the teeth of the gear 26^a and the gear 51. Springs 36^a and gravity normally hold the handle in the neutral and disengaged position.

To manually traverse the saddle, the handle 31^a is moved to engage the teeth 34^a thereof with the gear 51 whereupon the pinion 38 can be rotated in either direction as desired, the clutch 43 being in the neutral position. To power traverse the saddle from the arm shaft 10, the handle 15 31^a is moved to engage the teeth 33^a thereof with the teeth of the gear 26^a. The clutch can thereupon be shifted in either direction to power traverse the carriage in either direction as desired. It will be noted that 20 the several novel and advantageous features heretofore pointed out in reference to the mechanism shown in Figs. 1 to 4 are also retained in the operating and controlling mechanism just described.

25 It will be understood that the novel means above described can be applied to various forms of machine tools. In Figs. 8 to 10, I have illustrated the novel mechanism shown in Figs. 1 to 4 as applied to a lathe 30 to traverse the tool saddle or carriage thereof. The tool carriage 52 is slidably mounted on the ways of the lathe bed 53. A rack 54 secured to the under side of the bed is engaged by a pinion 55 on a shaft 56 rotatably mounted in the carriage. A gear 57 on the shaft 56 is engaged by a pinion 58 on a tubular shaft 16'. The tubular shaft 16' and pinion 58 are operated from mechanism, including a motor 18' secured to the 40 carriage, corresponding to that shown in Figs. 1 to 4 and heretofore described. The motor 18' is also controlled from the switch operating rod 23' in the manner heretofore described. The reference characters used 45 to designate these corresponding parts are the corresponding reference characters of Figs. 1 to 4 primed. Further description of this mechanism and its operation is therefore believed to be unnecessary. It will 50 be understood that when the carriage is to be traversed manually or from the motor 18', the clutch gear 59 of the carriage feeding mechanism is in the neutral position illustrated in Fig. 8.

55 What I claim is:

1. In a machine tool, the combination of a support having a guideway thereon, a saddle slidably mounted on the guideway, a driving connection including a rotary element for moving the saddle on the support, a power element, a manually operable member, means adapted to be operated by the member for optionally rotating the rotary element manually or making connections to power rotate the rotary element

from the power element, and means normally retaining the member in its inoperative position.

2. In a machine tool, the combination of a support having a guideway thereon, a saddle slidably mounted on the guideway, a rack on the support, a pinion on the saddle engaging the rack, a power element, a manually operable member, means adapted to be operated by the member for optionally rotating the pinion manually or power rotating the pinion from the power element, and means normally retaining the member in its inoperative position.

3. In a machine tool, the combination of a support having a guideway thereon, a saddle slidably mounted on the guideway, a driving connection including a rotary element for moving the saddle on the support, a normally operative power element, a manually operable member, means adapted to be operated by the member for manually rotating the rotary element in either direction from the power element, and means operated by said member to rotate the power element in either direction.

4. In a machine tool, the combination of a support having a guideway thereon, a saddle slidably mounted on the guideway, a driving connection including a rotary element for moving the saddle on the support, a power element, a shaft operatively connected to the rotary element, a member coaxial of the shaft, a handle pivoted to the member, pivotal movement of the handle in one direction being adapted to connect the same with the shaft whereby the rotary element can be rotated manually, and means for controlling the rotation of the rotary element from the power element, pivotal movement of the handle in the opposite direction connecting the same with such means.

5. In a machine tool, the combination of a support having a guideway thereon, a saddle slidably mounted on the guideway, a driving connection including a rotary element for moving the saddle on the support, a power element, a shaft operatively connected to the rotary element, a member coaxial of the shaft, a handle pivoted to the member, pivotal movement of the handle in one direction being adapted to connect the same with the shaft whereby the rotary element can be rotated manually, means for controlling the rotation of the rotary element from the power element, movement of the handle in the opposite direction connecting the same with such means, and means normally holding the handle in the intermediate position.

6. In a machine tool, the combination of a support having a guideway thereon, a saddle slidably mounted on the guideway, a driving connection including a rotary ele-

ment for moving the saddle on the support, a motor on the saddle in constant driving connection with the rotary element, and means for manually rotating the element to hand traverse the saddle and for controlling the motor to power traverse the saddle.

7. In a machine tool, the combination of a support having a guideway thereon, a saddle slidably mounted on the guideway, a driving connection including a rotary element for moving the saddle on the support, a motor on the saddle in constant driving connection with the rotary element, a switch for controlling the motor, and unitary means for manually rotating the element to hand traverse the saddle and for operating the switch to power traverse the saddle in either direction.

8. In a machine tool, the combination of a support having a guideway thereon, a saddle slidably mounted on the guideway, a rack on the support, a pinion on the saddle engaging the rack, a motor on the saddle operatively connected to the pinion, a switch for controlling the motor, and a manually operable handle, the handle in one position being connected to the pinion whereby to hand traverse the saddle and in another position being connected to the switch to power traverse the saddle.

9. In a machine tool, the combination of a support having a guideway thereon, a saddle slidably mounted on the guideway, a driving connection including a rotary element for moving the saddle on the support, a motor on the saddle in constant driving connection with the rotary element, a switch for controlling the motor, a toothed element connected to the switch, a toothed element connected to the rotary element, and a

handle pivoted intermediate the toothed elements and having teeth for engaging such elements, pivotal movement of the handle in opposite directions being adapted to engage the teeth thereof with the two toothed elements respectively.

10. In a machine tool, the combination of a support having a guideway thereon, a saddle slidably mounted on the guideway, a driving connection including a shaft and a rotary element for moving the saddle on the support, a motor on the saddle operatively connected to the rotary element, a switch for controlling the motor, a switch controlling rod extending through the said shaft, a toothed element secured to the rod, a handle mounted on the rod adjacent the toothed element, movement of the handle in one direction connecting the same with the shaft for manually traversing the saddle and movement of the handle in the other direction connecting the same with the toothed element for operating the switch.

11. In a radial drill, the combination of a vertical column, a horizontal arm on the column, a saddle slidable on the arm, a driving connection including a rotary element for moving the saddle on the arm, a power element, a member for controlling the power drive therefrom to the rotary element, a member connected to the rotary element, and a handle between such members and movable to operatively engage either member, the handle being adapted to respectively control the power drive and manually rotate the rotary element when engaged with the said members respectively.

In testimony whereof, I hereto affix my signature.

ROSWELL H. RAUSCH.
